(57)

CLAIM

The ornamental design for a blister pack device, as shown and described.

DESCRIPTION

FIG. 1 illustrates a perspective view of a blister pack device, embodying our design, in an open position;

FIG. 2 illustrates a side view thereof;

FIG. 3 illustrates a top view thereof;

FIG. 4 illustrates a bottom view thereof;

FIG. 5 illustrates a front view thereof;

FIG. 6 illustrates a rear view thereof;

FIG. 7 illustrates a perspective view of the first embodiment of a blister pack device, embodying our design, in a closed position; and,

FIG. 8 illustrates a side view of the first embodiment of a blister pack device, embodying our design, in an open position as seen from the opposite side of FIG. 2.

DESCRIPTION

(51) LOC (8) Cl. **08-05**

FIG. 1 illustrates a perspective view of a blister pack device, embodying our design, in an open position;

(52) U.S. Cl. **D8/51; D8/98; D24/133**

FIG. 2 illustrates a side view thereof;

(58) Field of Classification Search **D8/14;**

FIG. 3 illustrates a top view thereof;

D8/51, 52, 98, 395; D24/133; 30/363, 364;

FIG. 4 illustrates a bottom view thereof;

221/25, 26, 131; D9/435

FIG. 5 illustrates a front view thereof;

See application file for complete search history.

FIG. 6 illustrates a rear view thereof;

(56) **References Cited**

FIG. 7 illustrates a perspective view of the first embodiment of a blister pack device, embodying our design, in a closed position; and,

U.S. PATENT DOCUMENTS

FIG. 8 illustrates a side view of the first embodiment of a blister pack device, embodying our design, in an open position as seen from the opposite side of FIG. 2.
